UNITED STATES PATENT OFFICE.

JOSEPH B. GREEN, OF SEATTLE, WASHINGTON, ASSIGNOR TO G. A. HENKEL, OF ARLINGTON, OREGON.

CONCENTRATOR.

1,216,798.

Specification of Letters Patent. Patented Feb. 20, 1917.

Application filed January 26, 1916. Serial No. 74,322.

To all whom it may concern:

Be it known that I, JOSEPH B. GREEN, a citizen of the United States, residing at Seattle, in the county of King and State 5 of Washington, have invented a certain new and useful Improvement in Concentrators, of which the following is a specification.

My invention relates to improvements in concentrators which are adapted for use in 10 the operation of extracting gold from the auriferous earth of placer mines, and the object of my invention is to provide a concentrator which shall be adapted efficiently and cheaply to eliminate the stones and 15 lighter non-gold-bearing portions of the earth of a placer mine from the heavier portions which carry the gold values thereof and then conduct such concentrated heavier portions into the receiving end of a gold- 20 saving device, as, for instance, into the distributing box of one of my gold-saving devices which is illustrated and described in United States Letters Patent No. 1,123,188 granted to me on date of December 29, 1914, 25 which gold-saving device may be operated to extract all of the gold contained in said concentrated heavier portions.

I accomplish this object by devices illustrated in the accompanying drawings, 30 wherein Figure 1 is a plan view of a structure embodying my invention; Fig. 2 is a view of the same in vertical section on broken line α , α of Fig. 1; Fig. 3 is a view of the same in vertical section on broken 35 line y , y of Fig. 1; Fig. 4 is a view of the same in vertical section on broken line z , z of Fig. 1; Fig. 5 is a view of the same in cross-section on broken line u , u of Fig. 1; Fig. 6 is a view of the same in cross-section 40 on broken line v , v of Fig. 1; Fig. 7 is a view of the same in cross-section on broken line w , w of Fig. 1; Fig. 8 is a view in side elevation of details of my invention associated with another detail thereof, which 45 other detail is shown in cross-section, while Fig. 9 is a view in side elevation of said first named details showing a modified form of said other detail in cross-section.

Referring to the drawings, throughout 50 which like reference numerals indicate like parts, 10 is a sluice box which is downwardly declined to adapt it to conduct water carrying mineral bearing earth of a placer mine on to the higher end portion of a 55 screening rack comprising downwardly de-

clined removable iron grizzly-bars 11 which are supported by cross-bars 47 and 49 which are disposed to extend between the inner surfaces of the opposite side walls 12 and 13 of a downwardly declined receptacle 17 upon whose bottom wall 15 are disposed a plurality of transversely disposed riffle-bars 16 of T shaped cross-section that are spaced from each other, as more clearly shown in Fig. 3.

The lower end of the receptacle 17 is connected with a chute 18 which extends obliquely therefrom in a left hand direction, its bottom 19 being flush with the top surface of the lowest one of the riffle-bars 16 whereby stone and the coarser pieces of the mineralized earthy material, which cannot pass between the grate-bars 11 nor between the riffle-bars 16, will be conducted into said chute 18 to be carried therethrough to a desired point.

Extending through the right hand side wall 13 of the receptacle 17 are a plurality of holes 20 which lead into a downwardly declined sluice box 21 and through which lighter and smaller pieces of the earthy material may be carried by water into said sluice box 21 which leads into the higher end of a downwardly declined receptacle 22.

On the outside surface of the right hand side wall 13 of the receptacle 17 is a plate 23 which is adapted to be adjusted vertically to vary the cross-sectional area of the holes 20 thus to control the flow of water and earthy material therethrough.

Upon the floor of the receptacle 22 is disposed an iron riffle member 24 which extends throughout the length of said receptacle 22 and from the right hand side wall 26 to a line at such distance from the left hand side wall 28 as will form a gutter, as shown in Fig. 1.

The top side of the riffle member 24 is serrated by grooves of angular cross-section, as grooves 25, which grooves 25 are disposed to extend obliquely downward from the side wall 26 into said gutter 27.

The floor of the gutter 27 is provided with a plurality of pockets 29, and extending through the side wall 28 from each of said pockets is a passageway which leads into a downwardly declined sluice box 30, through which passageways 29 water and earthy material may flow from said gutter 27 and from said pockets 29 into said sluice box 30.

The lower end of said receptacle 22 connects with a chute 31 into which may pass lighter and coarser earthy material and water which have not passed into the gutter 27 to be carried through the passageways 5 from the pockets 29 into the sluice box 30, said chute 31 extending obliquely to the right to a convenient point for the disposal of tailings.

The sluice box 30 is connected at its lower 10 end with another downwardly declined receptacle 32 and disposed on its floor is an iron riffle member 33, which is like the iron riffle member 24, except that its grooves are 15 smaller in cross-section and larger in number, and said riffle member 33 extends from the right hand wall 34 of the receptacle 32 to a line at such distance from the opposite wall 35 as will form a gutter 36, within the 20 floor of such gutter 36 are pockets 37 from which extend passageways through the bottom portion of the side wall 35, which passageways lead into a downwardly declined sluice box 38.

The lower end of said receptacle 32 connects with a chute 39 into which may pass lighter and coarser earthy material and water which has not passed into the gutter 36 to be carried through the passageways 30 from the pockets 37 into said sluice box 38, said chute 39 being extended obliquely to the right to a convenient point for the disposal of tailings.

The sluice box 38 is connected at its lower 35 end with a downwardly declined receptacle 40 upon the bottom of which are transversely disposed a plurality of riffle-bars 41 of T shaped cross-section, between which riffle-bars 41 the finer and heavier particles 40 of the mineral bearing earthy material carried by water may fall to the bottom of said receptacle 40 to pass therefrom outwardly through holes 42, formed in the side wall 43 of the receptacle 40, into a sluice box 44 45 which may conduct each concentrated mineral bearing earthy material into a gold saving device, not shown, while the lighter non-mineral bearing portion of said earthy material will be carried by water over the tops of said riffle-bars 41 to be discharged 50 into a chute 45 that is connected to the lower end of the receptacle 46, which chute 45 may be extended to a convenient point for disposal of tailings.

The holes 42 in the side wall 43, like the holes 20 in the side wall 13 of the receptacle 17, may be obstructed to a desired degree by a vertically adjustable board 46 disposed on the outside surface of said side wall 43, thus 60 to control the flow of water and the concentrated earthy material through said holes 42.

The iron grizzly-bars 11 are supported at their upper ends by the cross-bar 47 to which they are fastened by screw-bolts, as indicated in Figs. 1 and 3, each of which cross-

bars 47 is fastened at each end to the inner side of the side walls 12 and 13 respectively, while the lower ends of said grate-bars 11 rest each upon a stud 48, all of which studs are secured to the longitudinally slotted 70 cross-bar 49 which also is secured to the inner sides of the vertical walls 12 and 13, as more clearly shown in Fig. 5.

In Fig. 9, I have shown a grizzly-bar 50 which constitutes a modification of the grizzly-bar 11, and which in cross-section is formed to adapt it to be securely held in its position upon the top end portion of a stud 51 which corresponds in function to the stud 48, the top end portion of said stud 51 being 80 grooved to receive and hold the inwardly turned flanges formed on the under side of said grizzly-bar 50, while the lower end portion of said stud 51 is secured to a cross-bar 85 52 which corresponds in function to the cross-bar 49.

The modified form of the grizzly-bar 50 and the modified form of the stud 51, although more expensive to make, may be preferable since the lower end of such grizzly-bar 50 will be more securely held in its position than will the grizzly-bar 11.

The operation of my concentrator thus illustrated and described may be explained as follows: An ample sluice head of water 95 is supplied to the sluice box 10, and then mineral bearing earth of a placer mine is shoveled or fed into said sluice box 10 to be carried by the water flowing therein to the receptacle 17 to be discharged onto the upper 100 end portion of the grate-bars 11, whereupon such portions of said earthy material as consist of stones which are too large to fall between said grizzly-bar 11 will be carried throughout the length of said grate-bars 11 105 to be discharged into the chute 18, while the portions of such earthy material that fall between said grate-bars 11 are subjected to the washing action of the riffle-bars 16 and then pass outwardly through the holes 20 110 into the sluice box 21 to be conducted thereby into the receptacle 22 to fall on to the upper end of the riffle member 24, and the lighter and coarser non-mineral bearing 115 portions of said earthy material will be carried by water over said riffle member 24 throughout its length to be discharged into the chute 31, while the finer and heavier mineral bearing portions of said earthy material will be diverted sidewise to fall 120 into the gutter 27, thence into the pockets 29 and through the passageways therefrom into the sluice box to be conducted thereby into the receptacle 32 to fall on the upper end of the riffle member 33 whereupon other lighter 125 and valueless portions of said earthy material will be carried by water over the entire length of said riffle member 33 to be discharged into the chute 39, while the heavier and finer mineralized portions of said earthy 130

material will be diverted sidewise to fall into the gutter 27, thence into the pockets 29 and through the passageways therefrom into the sluice box to be conducted thereby into the receptacle 32 to fall on the upper end of the riffle member 33 whereupon other lighter and valueless portions of said earthy material will be carried by water over the entire length of said riffle member 33 to be discharged into the chute 39, while the heavier and finer mineralized portions of said earthy

material will be diverted sidewise into the gutter 36 to be carried thence into the pockets 37 and through the passageways therefrom into the sluice box 38 to be conducted into the receptacle 40 to fall upon the upper end of the series of transversely disposed riffle-bars 41 to be subjected to the action of said riffle-bars 41, whereby the non-mineralized lighter portions of said 5 earthly material will be carried over said riffle-bars 41 to be discharged into the chute 45, while all of the mineral bearing heavy portions of said earthly material, now constituting a highly concentrated mineralized mass of earthly material, will fall between said riffle-bars 41 to the bottom of the receptacle 40, thence to be carried therefrom through the passageways 42 into the sluice box 44 to be conducted thereby into a 10 gold saving device that will serve to separate the mineral values contained in said highly concentrated mineralized earthly material; for instance, the sluice box 44 might be extended to conduct such concentrated mass 15 of mineral bearing earthly material into the receiving end of a gold saving device like that described and illustrated in United States Letters Patent 1,123,188, granted to me on date of December 29, 1914, for gold 20 saving device, whereby there could be segregated all the gold contained in such concentrated mass of earthly material.

Manifestly, changes may be made in the forms, dimensions and arrangement of parts of my invention without departing from the 35 spirit thereof.

What I claim is:

1. In an ore concentrator including a sluice, the combination with longitudinally-extending grizzly bars, of a plurality of 40 transversely extending riffle bars mounted upon the sluice bottom beneath and spaced from the grizzly bars, said riffle bars being T-shaped in cross-section and being in successively lower horizontal planes with the 45 upper faces declined rearwardly.

2. In an ore concentrator including a sluice, the combination with longitudinally-extending grizzly bars, of transversely extending riffle bars mounted on the sluice 50 bottom and having flat upper faces and positioned beneath and spaced from the grizzly bars, the grizzly bars and upper faces of the riffle bars being arranged at acute angles with the riffle bars reversely inclined whereby the forward progress of material through the concentrator is retarded.

In witness whereof, I hereunto subscribe my name this fifteenth day of January, A. D., 1916.

JOSEPH B. GREEN.
